UNITED STATES PATENT OFFICE.

VICTOR PERSOONS, OF ASBURY PARK, NEW JERSEY.

WINDOW-SCAFFOLD.

1,145,263.

Specification of Letters Patent.

Patented July 6, 1915.

Application filed April 8, 1914. Serial No. 830,460.

To all whom it may concern:

Be it known that I, VICTOR PERSOONS, citizen of the United States, residing at Asbury Park, in the county of Monmouth and State of New Jersey, have invented certain new and useful Improvements in Window-Scaffolds, of which the following is a specification.

My invention relates to a new and useful improvement in supporting scaffolds or seats for use in window washing, the primary object of my invention being the provision of a supporting scaffold in the form of a chair which may be secured to and supported by the window casing and sill in such a manner that any one sitting in the seat or chair may readily wash the outside of a window to which it is applied.

A further object of my invention is to so construct the seat that it may be firmly held against either inward or outward movement with respect to the window casing and also against any tilting movement, thereby rendering it as safe as possible.

A still further object of my invention is to so construct the securing mechanism for the seat that it may be adjusted to windows of varying sizes and windows having sashes and sills of various proportions and types of construction.

With these and other objects in view, my invention will be more fully described, illustrated in the accompanying drawings, and then specifically pointed out in the claims which are attached to and form a part of this application.

In the drawings:—Figure 1 is a perspective view of my improved window washing seat in use; Fig. 2 is a top plan view of the seat in use, the window casing being shown in transverse section; Fig. 3 is a bottom plan view of the seat, showing certain details in construction; Fig. 4 is a side elevation of the window seat in use, the window sill being shown in vertical section to permit a full disclosure of the seat construction; Fig. 5 is an unassembled perspective view of the mechanism employed in locking the seat against outward movement from the window casing to which it is applied; Fig. 6 is an unassembled perspective view of one of the supporting feet and its adjustable attaching plate; Fig. 7 is a similar view of another supporting foot and its attaching plate.

Corresponding and like parts are referred

to in the following description and indicated in all the views of the drawings by the same reference characters.

My improved seat for window washers includes a seat frame 10 carrying a seat bottom 11, the frame being preferably formed of wood in the usual manner and the bottom of light wood or cane. This seat is reinforced and strengthened about its rear and side edges by a continuous strip of angle iron 12 bent to conform to the peripheral shape of the seat and secured by its horizontally extending flange to the lower face of the seat frame by a plurality of spaced fastening devices 13 such as bolts and nuts. The horizontal flange of this reinforcing element, at its ends, terminates a slight distance short of the front edge of the seat, while the vertical or depending flange has its end portions bent inwardly at right angles as shown at 14 to form securing ears, as will be later explained.

Diagonally disposed brackets 15 are secured at one end to the upper face of the seat at either side and the transversely extending back forming bar 16 is secured to the upper ends of these brackets. The bolts or other fastening devices 17 which secure the brackets to the seats also pass through the angle iron strip 12 and serve to additionally secure this strip to the seat. As best shown in Figs. 1 and 4, the depending flange of the angle iron strip 12, along the sides of the seat, is provided with horizontally extending slots 18, the purpose of which will be later fully explained.

In order to support and secure the above described seat exteriorly of a window by engagement with the window casing, I provide primarily an adjustable fastening device, indicated as a whole by the numeral 19, this fastening device being best shown in detail in Fig. 5 of the drawings. The device 19 primarily includes a guide member 20 and sliding arms 21 and 22 carried and supported by the guide 20. This guide 20 is in the form of a strip of metal, U-shaped in cross section and secured along the front portion of the chair seat, by bolts 23 passed through its intermediate portion and through the ears 14, previously described, the guide being so disposed that its side portions extend forwardly of the seat. This guide member is further provided with ears 24 which bear against the bottom face of the seat when the guide member is so fastened

to receive additional securing bolts or other fastening devices 25, the fastening devices 23 and 25 co-acting to not only hold the guide member against movement toward the 5 forward or rear portion of the seat but also against any turning about its longitudinal axis.

The guide member 20 has its intermediate portion thickened exteriorly as shown at 10 26 and adjacent this thickened portion the side portions or flanges of such member are connected by an integrally formed yoke 27 forming a guide loop, said flanges being similarly connected at their ends to form 15 guide loops 28 and 29. Reference to Fig. 3 of the drawings will disclose the fact that the guide loops 27 and 28 are equal in size, while the guide loop 29 is smaller, the reason for this proportioning being later apparent.

20 The supporting arms 21 and 22 each consist in a bar of metal provided throughout the greater portion of its length with a longitudinally disposed slot 30, these bars being proportioned to seat against the intermediate 25 portion of the guide member and between its flanges, lying one over the other as best shown in Fig. 3 with their outer ends extending beyond the guide loops 28 and 29, respectively. The inner ends of these supporting arms overlap under all circumstances and a wing bolt 31 has its shank passed through the aligned slots of these arms and threaded into a tapped bore formed in the thickened portion 26 of the guide member. 30 By mounting the supporting arms in this manner, they may be extended beyond the sides of the seat to any desired extent, within predetermined limits, and when so extended, firmly clamped by tightening the 35 wing bolt.

The intermediate portion of the guide member 20, adjacent the loop 28, is preferably thickened interiorly to provide a seat for the supporting arm 21 in a plane with 40 the outer face of the supporting arm 22 over which the inner end of the arm 21 extends. Because of this, both arms will be firmly clamped in place by tightening of the wing bolt. Each arm terminates in a substantially L-shaped window sash engaging head 50 45 55 60 65 70 75 80 85 90 95 100 105 110 115 120 125 130 135 140 145 150 155 160 165 170 175 180 185 190 195 200 205 210 ings and by proper manipulation of the wing nut 40, the supporting or clamping feet 37 are moved to engage snugly against the outer edge of the inner window sill or 5 the sill of the sash proper and clamped in such adjusted position. The supporting feet 46 are then adjusted to bear against the outer sill or window ledge in such a manner as to support the seat in horizontal 10 position, the supporting guides or brackets for such feet being preferably adjusted rearwardly of the seat in order that the feet may be located as far as possible toward the rear of the seat in adjusted position.

15 It will be clearly apparent that the supporting arms 21 and 22 prevent outward movement of the seat and, in conjunction with the supporting feet 37 and 46, prevent any swinging or tilting movement of 20 the seat. At the same time, the supporting feet 37 and 46, particularly the latter, serve to in effect support the rear portion of the seat and thus relieve the supporting arms 21 and 22 of the greater part of the strain 25 to which they would otherwise be subjected. The guide studs 35, carried by the securing plates 34, prevent all turning of the attached supporting feet and therefore insure proper engagement between such feet and 30 the outer edge of the inner window sill.

Although I have illustrated and described my invention in all its details of construction, it will of course be understood that I am not limited to such minor details, as various changes, within the scope of the ap-

pended claims, may be made at any time, without in the slightest degree departing from the spirit of my invention.

Having thus described the invention, what is claimed as new is:

1. A device of the character described including a seat, a reinforcing element extending around the back and sides of the seat and having a downwardly depending flange, a guide member secured across the front of the seat and to the ends of the reinforcing member, extensible arms carried by the guide member and movable into engagement with a window frame, and supporting members adjustably secured to the downwardly 45 depending flanges of those portions of the reinforcing member bracing the sides of the seat.

2. In a device of the character described, a seat, extensible arms carried by the forward portion of the seat and adapted to move into engagement with a window frame, a reinforcing element extending along the sides of the seat and having a depending flange, and a plurality of sill engaging devices carried by the flange at each side of the seat, all of said devices being adjustable longitudinally of the flange and the outermost devices being vertically extensible.

In testimony whereof I affix my signature 60 in presence of two witnesses.

VICTOR PERSOOONS. [L.S.]
